UNITED STATES PATENT OFFICE.

PAUL M. ZEIDLER, OF NEW YORK, N. Y., ASSIGNOR TO STRICH & ZEIDLER,
OF SAME PLACE.

DESIGN FOR AN UPPER FRAME FOR PIANOS.

SPECIFICATION forming part of Design No. 24,553, dated August 13, 1895.

Application filed May 31, 1895. Serial No. 551,337. Term of patent 7 years.

To all whom it may concern:

Be it known that I, PAUL M. ZEIDLER, a citizen of the United States, residing in the city, county, and State of New York, have invented and produced a new and original Design for Upper Frames for Pianos, of which the following is a specification.

My design relates to what are technically known in the art or trade of piano-making as "upper frames," constituting the upper front of panels or face-boards of upright pianos.

Figure 1 is a front elevation of an upright frame embodying my new design, and Fig. 2 a central transverse section thereof.

The distinguishing feature of my design consists in the upper frame, provided with the central decorative molding in the form of a semicircular arch and horizontal base, and in the side moldings in part concentric to said semicircular arch and in part parallel to the rectangular outline of the frame or front piece.

In the drawings, A represents the upper frame or front piece of a piano as a whole.

B is the central ornamentation, consisting 25 of the semicircular arch *b*, the ends of which are joined by the horizontal chord *b'*. The side decorations C C each consist of an inner molding *c* *c*, concentric with the semicircular arch *b*, and of horizontal molding *c' c'*, and 30 vertical moldings *c'*, the latter intersecting the horizontal moldings at right angles thereto.

My design is simple and artistic in appearance and harmonizes with the requirements of use.

What I claim is—

The design for the upper frame for upright pianos herein shown and described.

PAUL M. ZEIDLER.
